UNITED STATES PATENT OFFICE.

IRWIN S. CLIFFORD AND FRED C. TOMPKINS, OF MIAMI, ARIZONA.

TAILINGS-DISPOSAL APPARATUS.

1,271,134.

Specification of Letters Patent.

Patented July 2, 1918.

Application filed March 12, 1918. Serial No. 221,948.

To all whom it may concern:

Be it known that we, IRWIN S. CLIFFORD and FRED C. TOMPKINS, citizens of the United States, residing at Miami, in the 5 county of Gila and State of Arizona, have invented certain new and useful Improvements in Tailings-Disposal Apparatus, of which the following is a specification.

This invention relates to a separating and 10 automatic discharge apparatus adapted to separate the sand from the water in the tailings from mills and to discharge the sand into such position that it may be utilized in automatically building up the tailings dam 15 while the water is discharged at such point that after the proper settlement has taken place the water may be used over again in the treatment of ore.

The utility of the invention will be better appreciated if existing conditions are understood. Under the laws of many 20 States, it is no longer permissible for mining companies to permit the tailings to wash into and drift down the rivers and streams, since these tailings contaminate 25 the water, kill vegetation and, if the water carries enough of the tailings, becomes injurious to the stock which drink it. Therefore, many States have by statute compelled 30 the mining companies to keep these tailings out of the streams. One company in this locality now throws into their tailings pond about twenty thousand tons of tailings per day, these tailings being carried from the 35 mill in the launder or troughs which conduct the water. These tailings consist largely of sand and water and unless the sand is separated from the water, there will be enough water in the tailings to carry them 40 down the cañons into creeks and thence to the rivers, during high water, thereby subjecting the company to expensive suits for damages.

The present invention automatically separates the sand from the water, dumps the sand into such position as to build up a dam for the retention of the water or to create a tailings pond and discharges the water well out toward the center of the 50 pond.

In the accompanying drawings:

Figure 1 is a front elevation of an automatic separating and sand discharging apparatus constructed in accordance with the 55 invention:

Fig. 2 is a vertical sectional view therethrough:

Fig. 3 is a detailed view of a joint hereinafter described, and

Figs. 4 and 5 are detailed views of counterweight hangers hereinafter described. 60

Like numerals designate corresponding parts in all of the figures of the drawings.

Referring to the drawings, 5 designates spaced hanger brackets across the front faces 65 of which L-shaped angle 6 extends. Two forwardly extending L-shaped angles 7 are secured to the angle 6 by interposed plates 8. Braces 9 extend from the brackets 5 to the angles 7. A pair of L-shaped angles 10 70 is supported upon the angles 7 and a rod 11 passes between them. This rod has nuts 12 threaded thereupon, above and below the angles 10 and it carries at its lower end a tapering valve plug 13. The rod 11 and 75 valve plug 13 are fixed, though capable of vertical adjustment by means of the nuts 12. A sheet steel cone 14 is carried by hangers 15 and these hangers are pivoted at 16 to links 17. These links comprise spaced 80 bars which are separated at their upper ends by sleeves 18 through which bolts 19 pass and these sleeves have a bearing in recesses 20 of counterweight levers 21, said levers being pivoted at 22 between the outer ends 85 of the angles 10. Counterweight hangers 23 (see Figs. 4 and 5) have ends 24 adapted to engage the outer ends of the counterweight levers and they have stirrup-like lower portions 25 adapted to receive 90 weights 25.

The cone 14 is spanned by a guide bar 26 which maintains proper alinement between the cone and the rod 11. The valve 13 is adapted to have a seating in a valve seat 95 sleeve 27 which is held in position in the lower end of the cone by means of one or more set screws 28. These set screws are carried by a collar 29, by which the proper rigidity is imparted to the lower end of the 100 cone.

A partition wall 30 at the upper side of the cone forms a compartment 31. The upper end of this partition wall terminates short at the top of the cone so that as the 105 water rises in the cone it will overflow into the compartment 31. This compartment is provided with a cement bottom to prevent cutting-out of the same. The water which overflows into this compartment is dis- 110

charged through suitable connections indicated at 32, well out into the tailings pond.

It is to be understood that the apparatus herein shown and described is disposed in 5 position for the water from the launder or trough from the mill to be discharged into the cone. There will be approximately eighty-five per cent, water and fifteen per cent, sand in the tailings, although this varies. The sand will sink to the bottom of 10 the cone while the clearest water will overflow into the compartment 31 and be discharged through the connections 32 well out toward the center of the tailings pond, as 15 above stated. When a sufficient amount of sand has collected in the cone to overbalance the counterweights 25', the cone will move bodily downward and discharge a portion of this sand. The apparatus is disposed in such position as to discharge the 20 sand above and upon the tailings dam so that the dam is automatically kept up.

At the present time most of the mining companies are under great expense in maintaining men, teams and the like to keep up these dams and some companies have been forced to employ steam shovels in this work. The present invention performs the three-fold object of keeping up the dam, keeping 30 the tailings out of the streams and rivers and rendering it possible to use the water over and over again in their operations. This last is a point of considerable importance since, with many of these companies, 35 water is scarce and expensive.

It is to be understood that the invention is not limited to the precise construction set forth but that it includes within its purview whatever changes fairly come within the 40 spirit of the appended claims.

Having described our invention what we claim is:

1. A device of the character described comprising a pair of counterweighted levers, 45 a tank suspended therebetween, a fixed valve with which said tank co-operates and an overflow located at the upper portion of said tank.

2. A device of the character described 50 comprising a supporting frame work, a pair of counterweighted levers pivoted thereon, a conical receptacle lying between and suspended from said levers, a fixed rod carried

by said framework and a valve carried by 55 said fixed rod, the weights acting to move the receptacle into such position as to engage the valve and close the discharge from the receptacle, and the receptacle being movable under the weight of accumulated sand therein to discharging position, an overflow compartment within said receptacle adjacent the 60 top thereof and a lateral discharge from said overflow compartment.

3. A device of the character described comprising a supporting frame, a pair of oppositely projecting, pivoted, counterweighted levers carried by said frame, said levers having concave seats formed in their upper faces adjacent their inner ends, convex members seated in said recesses, links 65 hung from said convex members, a conical receptacle, members by which the conical receptacle is supported, said members being pivotally connected to the lower ends of the links, a vertically adjustable rod carried by 70 the frame, a valve carried by the rod and disposed within the receptacle and a lateral overflow from the receptacle.

4. In a device of the character described the combination with a fixed valve, a vertically movable counterweighted receptacle 80 co-operating therewith and acting under the weight of material contained therein to move away from said valve to thereby discharge the contents of the receptacle, an opening 85 formed in the side wall of the receptacle below the top thereof, a compartment, the upper edge of which terminates below the upper edge of the receptacle and which embraces the opening in the wall of the receptacle, a lateral discharge spout carried by 90 and bodily movable with the receptacle, and leading from said opening and a discharge conduit independent of the receptacle disposed below and in spaced relation to the 95 spout whereby vertical movement of the receptacle is permitted while the relation between the spout and the conduit is maintained.

In testimony whereof we affix our signatures in the presence of two witnesses.

IRWIN S. CLIFFORD.
FRED C. TOMPKINS.
